(57) **CLAIM**

The ornamental design for a cup caddy for coffee cups and the like, substantially as shown and described.

DESCRIPTION

FIG. 1 is an isometric view of a cup caddy for coffee cups and the like according to the invention showing the new design;

FIG. 2 is a front elevational view thereof;

FIG. 3 is a right side elevational view thereof, the left side view being an identical mirror image thereof;

FIG. 4 is a top plan view, the bottom view being identical thereof;

FIG. 5 is a rear elevational view thereof; and,

FIG. 6 is a view similar to FIG. 4 with tabs bent down.

The broken lines are for illustrative purposes only and form no part of the claimed design.
